UNITED STATES PATENT OFFICE.

GEORGE PICKFORD AND ELI JAGGER, OF OLDHAM, COUNTY OF LANCASSTER,
ENGLAND.

CAP FOR FOOT-STEPS FOR SPINNING-SPINDLES.

SPECIFICATION forming part of Letters Patent No. 357,226, dated February 8, 1887.

Application filed March 24, 1886. Serial No. 196,386. (Model.) Patented in England February 9, 1885, No. 1,752.

To all whom it may concern:-

Be it known that we, GEORGE PICKFORD and ELI JAGGER, subjects of the Queen of Great Britain and Ireland, and residents of Oldham, in the county of Lancaster, England, have jointly invented a new and useful Improvement in Caps for Foot-Steps for Spinning-Spindles, (patented in Great Britain and Ireland by Letters Patent No. 1,752, dated February 9, 1885,) of which the following is a specification.

This invention relates to covered or capped "foot-steps," and it consists, first, in the combination, with the step-rail and an ordinary foot-step having a cupped top flush with the rail, of a peculiarly-constructed cap having a downwardly-projecting foot-rim which rests upon the rail, an elevated concaved or cupped top, which facilitates introducing the lubricant, and beneath said top a contracted inner shield, which confines the oil thrown off by the spindle and insures its immediate return to the step-chamber, the whole serving to exclude dust and dirt from the step-bearing and to economize oil without interfering with a rapid oiling operation nor with cleaning out the bearings when this is required.

It consists, further, in a specific cap adapted to be employed and constructed, as herein-after set forth, so as to be cheaply manufactured in a superior form.

A sheet of drawings accompanies this specification as a part thereof.

Figures 1, 2, and 3 of these drawings are vertical sections of peculiarly-capped foot-steps illustrating this invention, the same being shown as applied to a single rail. Fig. 4 is a like view of a preferred species of such peculiarly-capped foot-steps.

Like letters of reference indicate corresponding parts in the several figures.

Each of said peculiarly-capped foot-steps comprises what we term an "ordinary" foot-step, *a*—that is to say, one having a dished top, *b*, and sunk flush with the top of the rail *c*, which supports it. The remainder of each of said capped foot-steps is a shield or cap, *d*, having a downwardly-projecting foot-rim, *e*, which rests on the rail around the foot-step proper, a concave or cupped top, *f*, which fa-

cilitates filling the bearings in customary manner, and a contracted inner shield, *g*, which surrounds that portion of the spindle immediately above its contracted extremity or foot and arrests the oil thrown off by centrifugal force, so as to insure its immediate return to the step-bearing. The whole is annular, so as to fit loosely around the spindle, and is supported in effective position by said foot-rim *e*, resting upon the rail *c*, as aforesaid.

The caps *d*, Figs. 1 and 2, are each composed of three parts, their said foot-rims *e*, cupped tops *f*, and inner shields, *g*, being formed separately of stamped sheet metal and the latter of cup shapes. In the former, Fig. 1, all said parts are united at the perimeter of the cap by a seam, *h*, formed by upsetting the edge of the top disk. In that form shown in Fig. 2 the top disk and inner shield are so united; but the foot-rim *e* embraces a cylindrical portion, *i*, of the inner shield, so as to slide lengthwise thereon, which provides for adjusting the cap to more or less shallow foot-steps, as illustrated by dotted lines in the figure.

The cap *d*, Fig. 3, is struck up from sheet metal in one part, and its inner shield, *g*, is in the form of a depending cylindrical neck having a notch or notches, *j*, at its lower end, for the passage of oil into and out of that portion of the step-chamber *b* outside thereof.

The cap *d*, Fig. 4, is composed of two parts, each formed of stamped sheet metal, its said foot-rim *e* and cupped top *f* being formed in one part and united with an inner shield, *g*, of inverted-cup shape, by a central eyelet-joint, *k*. So forming and uniting the parts insures a smooth frictionless waist opening to embrace the spindle, and at the same time provides for cheaply manufacturing a superior form of the cap for general use.

For cleaning out the foot-steps the caps may be simply lifted or removed, for which purpose, it will be observed, the cap is in each case adapted to be readily grasped between finger and thumb.

In lubricating the spindles the oil is poured into the cupped top of each cap and quickly finds its way into the step-chamber below, while the latter, during this operation and ordinarily, remains covered, so as to preclude

the escape of oil and the entrance of the larger flying particles of "dust" and "dirt."

Having thus described our said improvement in foot-steps for spindles, we claim as our invention and desire to patent under this specification—

1. In combination with the rail and an ordinary foot-step embedded therein and having a cupped top flush with the rail, a cap concentric with the step-bearing, comprising a foot-rim which rests on said rail, an elevated cupped top, and an inner shield depending within said foot-rim, substantially as herein specified.

2. The within-described two-part foot-step cap, comprising a foot-rim and a cupped top in one part, and an inner shield of inverted-cup shape united with the former by a central eyelet-joint, substantially as herein specified, for the purpose set forth.

In testimony whereof we affix our signatures in presence of two witnesses.

GEORGE PICKFORD.
ELI JAGGER.
